DESIGN FOR A REMOTE CONTROL REPRODUCER CASING OR SIMILAR ARTICLE

Lloyd J. Andres, Chicago, Ill., assignor to Automatic Instrument Company, Grand Rapids, Mich., a corporation of Michigan

Application April 13, 1939, Serial No. 84,255

Term of patent 7 years

To all whom it may concern:

Be it known that I, Lloyd J. Andres, a citizen of the United States and resident of Chicago, in the county of Cook and State of Illinois, have invented a new, original, and ornamental Design for a Remote Control Reproducer Casing or Similar Article, of which the following is a specification, reference being had to the accompanying drawing, forming part thereof.

Fig. 1 is a perspective view of the remote con-

trol reproducer casing or similar article, showing my new design.

Fig. 2 is a top plan view of the casing.

The left-hand portion of the cabinet is identical to the right-hand portion.

I claim:

The ornamental design for a remote control reproducer casing or similar article, as shown and described.

LLOYD J. ANDRES.
